UNITED STATES PATENT OFFICE.

HALFORD W. PARK, OF SCARSDALE, NEW YORK, ASSIGNOR TO ROCKWOOD SPRINKLER COMPANY OF MASSACHUSETTS, OF WORCESTER, MASSACHUSETTS, A CORPORATION OF MASSACHUSETTS.

AUTOMATIC DEVICE FOR DRAINING VARIABLE-PRESSURE-ALARM SYSTEMS.

Application filed December 31, 1921. Serial No. 526,428.

To all whom it may concern:

Be it known that I, HALFORD W. PARK, a citizen of the United States, residing at Scarsdale, in the county of Westchester and 5 State of New York, have invented a new and useful Automatic Device for Draining Variable-Pressure-Alarm Systems, of which the following is a specification.

This invention relates to an automatic device for controlling the supply and discharge of water under pressure for operating a fire alarm in connection with an automatic sprinkler system.

The principal objects of the invention are 15 to provide means which will insure that when the alarm valve check lifts from its seat due to a flow of water past it to supply an open sprinkler all the water discharged through the pipe and spaces connecting the 20 annular port of the alarm valve with the gong-actuating mechanism will be utilized without waste for alarm purposes, to provide means which will insure that when the check closes the water thereby left trapped 25 in the alarm valve system will be drained forthwith leaving the alarm valve connecting pipe and spaces in their normally empty condition and thus automatically ready for further operation; to provide a construction 30 in which, although both of the above objects are attained, no alarm will result from the uncovering of the annular port as the effect of mere water hammers transmitted to the alarm valve by the water in the supply 35 pipe of the sprinkler system; to provide a system in which there are no moving parts except a diaphragm and valve, nothing to create friction and nothing to corrode.

Further objects and advantages of the invention will appear hereinafter.

Reference is to be had to the accompanying drawing which is a sectional view of a part of a sprinkler system showing a preferred form of this invention applied 45 thereto.

I have shown the invention as used in connection with a variable pressure alarm or check valve 10, in this instance used in connection with a water main 11 under high 50 pressure and a stand pipe 12 to which the various sprinkler heads are connected. When the valve 10 opens, either on account of reduction in the pressure above it, or for any other reason, water will flow as usual

through a pipe 13, the end of which is connected with an annular port in the valve seat which is normally closed by the valve 10. The pipe 13 is shown as feeding the usual retarding chamber 16 which is connected by a pipe 17 with a water motor 60 alarm device 9, located at any desired place and adapted to be operated by the flow of water from the retarding chamber to sound an alarm. The parts so far described are of the usual construction and serve the usual 65 purposes. This invention does not need to be used with a retarding chamber, as it can serve for retarding purposes itself to prevent sounding of the alarm in case of water hammer, with modifications within the skill 70 of those skilled in the art.

In order to discharge the water from the retarding chamber it has been customary heretofore to provide it with a constantly open drain outlet of small area which will, 75 of course, discharge water all the time the retarding chamber is being filled and all the time that the alarm is operated. In order to secure sufficient operating pressure at the gong this drain opening has to be 80 made small and therefore it takes a long time for the retarding chamber and connecting pipes to be drained by it after the alarm valve 10 is closed. As stated above, this invention involves means by which all the 85 water that flows by the alarm valve 10 through the pipe 13 will be delivered into the retarding chamber or the alarm motor system without waste and when the valve 10 closes again the water will immediately discharge from the retarding chamber into the atmosphere at a rapid rate and this discharge will continue until the retarding 90 chamber and connecting pipes and spaces are empty. The rapidity with which the 95 parts are brought back to normal condition for operation again permits the real function of the retarding chamber to be maintained by preventing water hammers, even if occurring in close succession from starting the alarm to operate.

For these purposes I can attach the device anywhere in the pipe line between the alarm valve 10 and the water motor 9, but I have shown it as connected to the bottom 105 of the retarding chamber. Below the pipe 13 there is a pipe 21 provided at the top with a Pitot tube 22 in the pipe 13. This

is turned toward the alarm valve 10 and therefore when water flows toward the retarding chamber from the main valve some of it will be forced to flow down this tube 5 and through the pipe 21 into a pressure chamber 23. This exerts considerable pressure on a flexible diaphragm 24 constituting the top of that chamber. Above this chamber and diaphragm is a second or suction chamber 26. Attached to the diaphragm in the suction chamber is a weighted valve 29 which can be made, if desired, of Monel metal. Just above this valve is a valve seat 28, having a large port 30 through it, which 10 also can be formed of Monel metal. This port communicates with a discharge pipe at the top for discharging water from the system into the open air.

Also communicating with the top of the 20 suction chamber 26 there is a pipe 33 leading into the pipe 13. At the top of this there is a Pitot tube 35 somewhat larger than the tube 22 and with its curved end turned in the opposite direction.

25 When the clapper of the main alarm valve is shut and the system is drained there is very little hydrostatic pressure on the opposite surfaces of the diaphragm in the two chambers and what there is is substantially 30 equal. The valve 29 therefore remains in its lowest position leaving the vent hole 30 open to the atmosphere. Whenever the valve 10 opens and the water starts to flow into the retarding chamber, the action of 35 this flow of water unbalances the pressure in the two chambers 23 and 26.

The unbalancing of the pressure is caused 40 by two forces assisting each other. The first force is the difference in the hydrostatic pressure on the two chambers. The pressure on the pressure chamber is greater than the pressure on the suction chamber because the former is a closed chamber while the latter is open to the atmosphere. The second force is the difference in pressure on 45 the two chambers due to the Pitot tubes. The velocity of the water through the pipe 13 causes an additional pressure on the opening of the Pitot tube 22 connected to the pressure chamber, which additional pressure 50 is transmitted to the lower surface of the diaphragm. The velocity of the water through the pipe 13 causes a reduction in pressure on the Pitot tube 35 connected to the upper chamber which reduction in pressure 55 is transmitted to the upper surface of the diaphragm. Either the difference in the force of the hydrostatic heads alone, or the difference in velocity heads alone will 60 cause the diaphragm to rise. The valve having once risen it will remain on the valve seat holding the vent hole closed as long as water is flowing in the pipe.

65 As soon as the water flow stops, however, the difference in velocity head disappears

and the hydrostatic heads on the two chambers becomes equal so that the diaphragm tends to fall back to the position shown. The only force holding the valve up to the valve seat is the hydrostatic pressure due to the 70 head of water from the water motor acting on the valve in the vent hole. The cast iron weight is heavy enough so that this head will not support it and it falls back into its original position leaving the vent 75 hole open and free to drain the retarding chamber, which completes the operation. It will be noted that when the valve seats on the vent hole, then the hydrostatic head on each chamber becomes equal, as both chambers becomes closed to the atmosphere, therefore, were it not for the Pitot tubes the valve would fall away from the vent hole. The 80 difference in velocity head due to the tubes is the force that holds the valve on the seat 85 while water is flowing.

It is to be observed that while the water is flowing the force holding the valve on its seat continually increases until the maximum force is obtained when the retarding 90 chamber and the pipe to the water motor nozzle are completely filled. If there should be a slight leak around the valve 29 while it is seated it would not affect the operation 95 of the alarm. It is to be noted that there are no moving parts in the device except the diaphragm and nothing to present any friction or to make it possible for the parts to corrode or fail to operate. It depends solely 100 and directly upon the laws of hydrostatics.

Although I have illustrated and described only a single form of the invention, I am aware of the fact that modifications can be made therein by any person skilled in the art without departing from the scope of the 105 invention as expressed in the claims. Therefore, I do not wish to be limited to all the details of construction herein shown and described but what I do claim is:—

1. In an automatic alarm valve system, 110 the combination with a main alarm valve, a water motor alarm, and a conduit controlled by the alarm valve for conducting water from the riser to the motor when the alarm valve opens, of an upwardly opening port 115 for discharging the water from the system, a valve below it adapted to close the port from below and adapted to open the port by force of gravity, a diaphragm having a chamber behind it, means for conducting water to increase the pressure in said chamber when the water flows to the water motor, whereby said valve is held up in opposition to its weight against the valve seat to close it by the force of the water flowing 120 through the system from the riser to the water motor and whereby when it becomes seated the hydrostatic head of water above it will assist in holding it to its seat, said valve having sufficient weight to cause it to 125 130

fall away from the seat whenever held only by the hydrostatic head in the system behind said diaphragm.

2. In a device of the character described, 5 the combination of a retarding chamber, a conduit for leading water thereto, a valve seat opening upwardly for discharging the water therefrom connected with said conduit, a chamber below the valve seat, an upwardly operating valve in said chamber, a 10 pressure chamber connected with said conduit, means whereby the flow of water along the conduit will increase the pressure in the pressure chamber, said valve having a weight sufficient to cause it to drop away 15 from the seat when held to it by nothing but the hydrostatic head above it in said retarding chamber and system, a diaphragm separating said chambers and supporting 20 said valve, and means whereby when the valve has once closed the hydrostatic head will assist in holding it against the seat.

3. In a device of the character described, the combination with an alarm motor and 25 a pipe for conducting water thereto, of a Pitot tube projecting into said pipe and having its curved admission end extending toward the source of pressure in the conduit, two chambers below the pipe one communicating with said tube, the other chamber having an outlet port at the top and communicating with the pipe, a valve in the second chamber, adapted to rise therein and close the port, and a diaphragm separating said chambers and connected with the 30 valve for transmitting the pressure due to the velocity of water past the Pitot tube to said valve to cause it to be elevated and seated.

4. In a device of the character described, 40 the combination with a retarding chamber and a pipe for conducting water thereto, of a pair of Pitot tubes extending from said pipe and projecting into it in opposite directions, two chambers below the conduit, each communicating with one of said tubes, one of said chambers constituting a pressure chamber, the Pitot tube communicating with which has its curved admission end 45 extending toward the source of pressure in the conduit, the other chamber having an outlet opening at the top and also communicating with the other Pitot tube, a valve in the second chamber adapted to rise there- 50 in and close the outlet port, and a flexible diaphragm between the two chambers to which diaphragm the valve is connected.

5. In a device of the character described, 55 the combination with a retarding chamber and a conduit for conducting water thereto, of a Pitot tube extending from said conduit and projecting into it, two chambers below the conduit, the Pitot tube communicating with one of said chambers and having its

curved admission end extending toward the 65 source of pressure in the conduit, the other chamber having an outlet opening at the top and also communicating with the conduit, a valve in the second chamber adapted to rise therein and close the port, and a flexible 70 diaphragm separating said chambers for transmitting the pressure due to the velocity of water past the Pitot tube to said valve to cause it to be seated, on which diaphragm is a weight located in the pressure chamber, 75 said valve being attached to the top of said diaphragm.

6. In a device of the character described, the combination with a conduit for conducting water, of a Pitot tube extending from 80 said conduit and projecting into it two chambers, the Pitot tube communicating with one of said chambers and having its curved admission end extending toward the source of pressure in the conduit, the other 85 chamber having an outlet opening and communicating with the conduit, a valve in the second chamber adapted to close the port, and a flexible diaphragm separating said chambers for transmitting the pressure 90 due to the velocity of water past the Pitot tube to said valve to cause it to be seated, said valve being attached to said diaphragm.

7. In an automatic alarm valve system the combination with a main alarm valve, a 95 water motor alarm, and a conduit controlled by the alarm valve for conducting water from the riser to the motor when the alarm valve opens, of a port for discharging the water from the system, a valve adapted to 100 close the port, a diaphragm having a chamber behind it, means for directing the water in a course to increase the pressure in said chamber when the water flows to the water motor, whereby said valve is held against 105 the valve seat to close it by the force of the water flowing through the system from the riser to the water motor and whereby when it becomes seated the hydrostatic head of water above it will assist in holding it to its 110 seat.

8. In an automatic alarm valve system the combination with a main alarm valve, a water motor alarm, and a conduit controlled by the alarm valve for conducting water from the riser to the motor when the alarm valve opens, of a port for discharging the water from the system, a valve adapted to close the port, a diaphragm having a chamber beyond it, means whereby the pressure in 115 said chamber is decreased when the water flows to the water motor, whereby said valve is held against the valve seat to close it by the force of the water flowing through the system from the riser to the water motor. 120

In testimony whereof I have hereunto affixed my signature.

HALFORD W. PARK.
